UNITED STATES PATENT OFFICE.

EDWIN S. VOTEY, OF SUMMIT, NEW JERSEY, ASSIGNOR TO AEOLIAN COMPANY, OF NEW YORK, N. Y., A CORPORATION OF CONNECTICUT.

MUSICAL-INSTRUMENT PLAYER.

No. 829,184.

Specification of Letters Patent.

Patented Aug. 21, 1908.

Application filed January 27, 1905. Serial No. 242,987.

To all whom it may concern:

Be it known that I, EDWIN S. VOTEY, a citizen of the United States, and a resident of Summit, in the county of Union and State of New Jersey, have invented certain new and useful Improvements in Musical-Instrument Players, of which the following is a specification.

My invention relates to a mechanical player for musical instruments, and provides such a player which may be removably secured within the casing of any suitable musical instrument.

By making the parts removable in a few integral parts from the instrument by a person of ordinary skill the replacing, *e. g.*, of a broken or defective string in a piano is greatly facilitated. In addition the construction of my device enables it to be placed in, *e. g.*, an upright piano of the ordinary type with little alteration and with a minimum of adaptation.

In the preferred form of embodiment of my invention shown in the drawings, Figure 1 represents in vertical section so much of an upright piano as is necessary to show my invention. Figs. 2 and 3 are similar views of the lower portion of the piano, showing my device in different positions. Fig. 4 is an elevation of the part shown in Fig. 3, a portion of the casing being removed. Fig. 5 shows a detail. Fig. 6 is a vertical transverse section on the line 6 6, Fig. 8. Figs. 7 and 8 are vertical sections on the lines 7 7 and 8 8, Fig. 6.

1 designates the casing of the instrument, of which 11 is the bottom, 12 the removable lower front, having a hinged drop portion 13, 14, the key-bed, and 15 the removable upper front portion. 21 designates one of the keys of the piano, and 22 one of its strings. Interposed between these are the usual action parts, including hammer 23, jack 24, supported on jack-beam 25, and riser 26, extending from the capstan-screw 27 of the key 21 to the jack-beam, which latter has a forwardly-extending nose 28. All these parts I have represented fragmentarily and to some extent conventionally, as they form *per se* no part of my invention.

Secured on the bottom board 11 in front of the frame of the piano and in front of the strings 22 are two cheeks 31, having ovoid

recesses 32 in their upper faces. Approximately above these are other cheeks 33, secured to the lower side of the key-bed 14. As shown, the entire air-pressure or suction producing and storing portion of the mechanical player comprising bellows 41, wind-chest 42, bellows-pedals 43, connecting-pipe 44, and other well-known or necessary parts are secured to or supported by a chest or board 4. At the lower and upper corners of the board 4 are secured laterally-extending wings 45 46, respectively. In each of the lower wings 45 is screwed a vertical bolt or pin 47, the lower end of which is rounded to enter the recess 32 and to seat itself at the bottom thereof. Projecting forwardly from each of the upper wings 46 is a bar 471, having a longitudinal slot 48, adapted to receive the head of a screw 49, which enters the cheek-pieces 33. When the pedals are in their folded position, as shown in Fig. 3 of the drawings, and the front portion 12 of the casing 1 has been removed, the board 4, carrying the wind-chest and all its connected parts, may be easily inserted into or removed from its place. To insert it, the ends of the bolts or pins 47 are stepped in the recesses 32 in the cheeks 31, the board 4 rocked back into place, and the screws 49 inserted through the slots 48 into the cheek-pieces 33. By reason of the vertical adjustability of the bolts 47 and of the play of the slots 48 on the screws 49 before these last are set home the board may be adjusted as desired—*e. g.*, to fit the end of the connecting-pipe 44 tightly against or into the corresponding aperture 141, bored through the key-bed 14.

I have illustrated the bellows-pedals 43 as of the well-known folding type, because this form of pedal is convenient to my construction; but it is evident that in this particular, as in other details of construction and arrangement, I am not limited to the preferred form shown or described.

Above the key-bed 14 and keys 21 in front of the frame and of the strings 22, stretched thereon, and behind the upper front portion 15 of the casing 1 of the instrument I removably support the pneumatics 51, primary, intermediate, and striking, the music-sheet motor 52, and all those parts of a mechanical player commonly called the "action." As shown, these are mounted upon, hung be-

neath, or otherwise supported by a board 5, which extends between the sides of the casing 1.

Secured to the casing 1 below the ends of the board 5 are check-pieces 34, slotted at 35 to retain strips 36. In the lower side of the board 5 are cut grooves 53, adapted to slide on the strips 36. The board 5, with the action supported thereon, is slid directly backward into the casing 1 and is locked firmly and held downward on the cheeks 34 by levers 58, pivotally attached to the inner sides of the casing 1 at 59. (Vide Fig. 7.) From each of the striking-pneumatics 51 rises a rod 54, at the upper end of which may be formed a rounded head 55, engaging with the nose 28 of the jacket-beam 25.

I have shown controlling-levers 61, which may serve as usual to alter the tempo, direct the accentuation, reverse the motor for rewinding, &c. As shown, each of these levers 61, of which four are indicated in the drawings, is pivoted to a board 6, the ends 62 of which slide into slots 111 in the casing 1. The board 6 is shown as having a drop front 63, hinged at 64. The rear end 65 of the lever 61 may be forked to engage with the ends 56 of the connecting parts 57, only one of which is shown. By "lever" I mean of course to include variations in form, whether finger-stops, handles, buttons, slides, or the like controlling means.

As in the case of the wind-chest and connected parts above described, it will be seen that the mechanical playing parts are easily insertible and removable. The board 6 and connected parts simply slide forward for removal. So, also, the board 5, on which the entire action depends, slides forwardly on the strips 36, the front portion 15 and board 6 being first removed and the levers 56 rocked on their pivots 57 out of their locking position. In replacing the board 5 and connected parts the heads 55 of the rods 54 pass easily under the noses 28 of the jack-beams 25.

It is of course understood that the drop front 63 is retained in its full-line position, Fig. 6, while the instrument is being played manually and is turned to the position shown in dotted lines in that figure when the mechanical player is being operated and it is desirable to use the levers 61.

The position of the music-roll immediately in front of the eyes of the player and the placing of the controlling-levers above the keyboard and beneath the music-roll enables the player to assume an erect and natural position and to readily and pleasantly manipulate the levers.

It is evident that many mechanical alterations may be made in the form, construction, and arrangement of parts without departing from my invention and that parts of the invention may be used advantageously

without the others. It is also to be noted that the terms used—e. g., the word "board"—as applied to the parts marked 4 and 5 in this embodiment of the invention are not intended to be limited to a particular material or form.

Where in the claims I speak of the key-bed of the instrument as "fixed," I intend to include one which is secured in any desired manner within the casing of the instrument, provided that it is so fixed therein as not to require removal or displacement for the removal of the wind-chest and connected parts which are placed beneath it or the pneumatic action of the instrument-player, which is placed above it.

It will of course be understood that the details of the pneumatics within the action and the various pneumatic chambers or passages in the chest or board 4 and in the other parts of the apparatus are entirely foreign to the essentials of the present invention and are, moreover, so well understood in the art as to require no exemplification or illustration.

Having thus described my invention, what I claim, and desire to secure by Letters Patent, is—

1. In a mechanical musical instrument a casing and a key-bed, a wind-chest, bellows and bellows-pedals located entirely beneath said key-bed, and means for integrally and detachably supporting said wind-chest, bellows and bellows-pedals and for removing them without movement of said key-bed.

2. In a mechanical musical instrument a casing and a key-bed, an action mounted in said casing above said key-bed, a controlling-lever for said action, and a part removably secured in said casing above said key-bed on which said controlling-lever is mounted.

3. In a mechanical musical instrument a casing and a key-bed, an action detachably connected with said casing above said key-bed, a controlling-lever for said action, and a part removably secured in said casing above said key-bed on which said controlling-lever is mounted.

4. In a mechanical musical instrument a casing and a key-bed, an action removably mounted in said casing above said key-bed, a controlling-lever for said action, and a part on which said lever is mounted above said key-bed, said part being removable from said casing separately from said action.

5. In a mechanical musical instrument a casing provided with a movable front portion, a key-bed and sound-producing devices, a mechanical instrument-player having a wind-chest, bellows and bellows-pedals located entirely beneath said key-bed, and means for integrally and detachably supporting said wind-chest, bellows and bellows-pedals and for removing same without movement of said key-bed.

6. In a mechanical musical instrument a casing provided with a movable front portion, a key-bed and sound-producing devices, a mechanical instrument-player having a part removably secured in said casing beneath said key-bed and in front of said sound-producing devices, a wind-chest, bellows and folding bellows-pedals mounted on said part, and means for integrally and detachably supporting said part and for removing same without movement of said key-bed.
7. In combination with a musical instrument having a casing provided with a movable front portion and sound-producing devices; a mechanical instrument-player having an action mounted in said casing in front of said sound-producing devices, a controlling-lever for said action, and a part removably secured in said casing on which said lever is mounted.
8. In combination with a musical instrument having a casing provided with a movable front portion and sound-producing devices; a mechanical instrument-player having an action mounted in said casing in front of said sound-producing devices, a controlling-lever detachably connected with said action, and a part removably secured in said casing on which said lever is mounted.
9. In combination with a musical instrument having a casing provided with a movable front portion and sound-producing devices; a mechanical instrument-player having an action removably mounted in said casing in front of said sound-producing devices, a controlling-lever detachably connected with said action, and a part on which said lever is mounted, said part being removable from said casing separately from said action.
10. In combination with an upright piano having a removable apertured front portion below the key-bed, a part removably secured within the casing in front of the strings and below the key-bed of said piano, a wind-chest and bellows mounted on said part, and bellows-pedals pivotally mounted on said part to pass through the aperture in said front portion said part being detachably supported and removable without movement of said key-bed.
11. In combination with an upright piano having a movable front portion below its key-bed, a board, wind-chest and bellows mounted on said board, engaging means within the casing in front of the strings and below the key-bed of said piano, and coöperating means on said board for engaging with said first-named engaging means said board and the parts mounted thereon being removable from the casing of said piano without movement of the key-bed.
12. In combination with an upright piano having a movable front portion below its key-bed, a board, wind-chest and bellows mounted on said board, engaging means within the casing in front of the strings and below the key-bed of said piano, coöperating means on said board for engaging with said first-named engaging means, and means for adjusting said board in said casing said board and the parts mounted thereon being removable from the casing of the piano without movement of the key-bed.
13. In combination with a musical instrument having a casing and a keyboard, an action of a mechanical instrument-player within said casing, a part removably mounted in said casing above said keyboard, and a controlling-lever operatively connected with said action, adjustably mounted on said part and extending out of said casing.
14. In combination with a musical instrument having a casing and a keyboard, an action of a mechanical instrument-player within said casing, a part removably mounted in said casing above said keyboard, a controlling-lever operatively connected with said action, adjustably mounted on said part and extending out of said casing, and a movable portion on said part for covering the outwardly-extending end of said lever.
15. In a mechanical musical instrument a casing provided with a movable front portion, a fixed key-bed and sound-producing devices, a part adapted to be secured in said casing, a wind-chest, bellows and folding bellows-pedals mounted on said part, and means for detachably and removably securing said part and the wind-chest, bellows and folding bellows-pedals mounted thereon within said casing beneath said key-bed and in front of said sound-producing devices.
16. In combination in a keyboard musical instrument, a removable automatic action, one or more controlling-levers for the said action removably mounted upon the casing of the instrument above the keyboard thereof and a hinged cover mounted above the keyboard for covering the exposed portion of said controlling lever or levers.
- In testimony whereof I have signed this specification in the presence of two subscribing witnesses.
